ADAM F. TORRANCE, OF KANSAS CITY, MISSOURI.

DUPLEX ENVELOPE.

Application filed May 24, 1926. Serial No. 111,111.

This invention relates to duplex envelopes of that class for the transmission of first and third or fourth class mail matter. Envelopes of this class customarily comprise a large compartment for the lower class matter and a small compartment for the first class matter, and recipients are supposed to open both compartments. It is a common occurrence however, for the addressee after 10 removing the lower class mail matter, to cast the envelope aside without removing the first class matter. Such failure is ascribed to forgetfulness or to the fact that, as the envelope is usually turned back side up for 15 convenience in withdrawing the unsealed flap of the large compartment, the letter compartment on the front side is hidden from view and thus overlooked, and this is true of that class of duplex envelopes which 20 provides the first class compartment with a flap reaching around the lower edge of the envelope and superimposed on and secured to the back thereof, even if such flap bears a warning against oversight, and most 25 people invert the envelopes for the removal of the lower class matter with the right hand, and as a result the "warning" is likewise inverted and therefore can be readily overlooked. My object is to produce a duplex envelope having a securing flap for the 30 small or first class compartment at both the front side and the rear side of the large compartment, thus doubling the chances against overlooking and removing the first class mail matter. Another object is to provide the 35 first class compartment with a third or end opening and a flap at such end, and to secure such flap against the front side of the large compartment, usually by superimposing it 40 upon the flap of the large compartment so that when the latter is folded into the large compartment without securing the same, the end flap of the small compartment shall be likewise folded into the large compartment 45 and be un-noticeable.

Under certain conditions, as specified in the postal regulations, third or fourth class mail matter can be sealed. In such cases the flap of the large compartment is folded 50 around upon the back portion of the latter for sealing; and in this case it is essential that the end opening of the small compartment should be sealed, and if such compartment has an end opening and an end flap, 55 such flap must be secured to the large compartment, and preferably to the flap thereof,

so that when the flap of the large compartment is severed to give access to the compartment, the sealing end flap of the small or first class compartment is likewise severed 60 so as to give access at the same time to the contents of the small or first class compartment.

A still further object is to provide a duplex envelope of such character that a single 65 address will satisfy the postal requirements for the transmission of both classes of mail matter. Another object is to provide a duplex envelope equipped with a sealing flap for the first class compartment which is 70 superimposed upon the back of the large compartment and an outline upon the back of the latter which in combination or co-operation with such sealing flap shall picture to the mind of the recipient the fact 75 that such combined features are representative of a first class mail matter container or compartment and thus serves as a guard against failure to obtain access to such compartment for the removal of the contents 80 thereof.

With these objects in view, the invention consists in certain novel and useful features of construction and combinations of parts as hereinafter described and claimed; and in 85 order that it may be fully understood, reference is to be had to the accompanying drawing, in which:—

Figure 1 is a perspective view of a duplex envelope embodying the invention, with the 90 first class compartment equipped with a top, bottom, and end flap.

Figure 2 is a perspective view of the envelope inverted to illustrate the bottom flap of the first class compartment as secured to 95 the rear side of the lower class compartment; and also illustrates an outline which in conjunction with said flap presents a picture or simulation of the small or first class compartment.

Figure 3 is an enlarged section on the line III—III of Figure 1.

Figure 4 is an enlarged section on the line IV—IV of Figure 1.

Figure 5 is a view of the blank before folding, of one type of first class compartment.

Figure 6 is a perspective view of the duplex envelope equipped with a modified form of the first class compartment.

Figure 7 is an enlarged section on the line VII—VII of Figure 6.

Figure 8 is a view of the blank which when folded provides the type of first class compartment illustrated by Figures 6 and 7.

In the said drawing, 1 indicates a large envelope or compartment suitable for containing low class mail matter, such as booklets, catalogues and the like, and said envelope or compartment is provided with a closing flap 2, preferably at the end, and susceptible of being sealed under certain conditions, as provided for in the postal regulations. There is nothing novel in the envelope or compartment 1 considered by itself, as it is nothing more or less than a large envelope of conventional type.

The small compartment identified generally by the character 3, consists in one form, of a generally elongated rectangular blank foldable transversely on the dotted line 4 to produce a rear side 5 and a front side 6. At the top of the rear side 5 there is a sealing flap 7 containing adhesive 8. At the bottom of side 6 there is a similar flap 9 having adhesive 10. The blank when folded on the line 4 is placed upon the face of the envelope 1 substantially as indicated by Figure 1, and by adhesive or equivalent means, is fastened permanently to the large envelope. The free end of side 6 is defined by the dotted line 11 and said side is provided with an extension constituting an end flap 12 containing adhesive, which flap is adapted to be superimposed upon the face of flap 2 of the envelope 1. To avoid the necessity of the user sealing all three flaps 7, 9 and 12, the manufacturer at the time the small envelope is permanently affixed to the large one, will ordinarily seal two of the flaps, leaving the third flap—selected by the user—to be sealed by the latter after the letter is inserted.

The sealing of the end flap 12 to the flap 2 not only assists in fastening the small envelope to the large one but incidentally seals the opening provided by the co-incident free ends of the sides 5 and 6. The two envelopes are then in condition for receiving the matter to be mailed, the first class matter or letter being inserted in the small envelope and there so sealed by the fastening down of the unsealed flap. The low class mail matter is then placed in the large envelope and either retained therein by tucking the flap 2 in place or by any equivalent and well known method. Under certain conditions the flap 2 may be sealed, which conditions are provided for by the postal regulations and have no bearing upon the question of invention here involved.

It is customary with an envelope of this character to use only one address, as the two compartments or envelopes are inseparably connected, it being necessary, however to place fourth class postage on the face of the large envelope and first class

postage on the face of the small envelope. It is also permissible to place printed notices or warnings against overlooking first class mail matter, but this has been omitted as it is conventional and forms no part of the invention, but it is not customary in duplex envelopes which have a bottom sealing flap which extends around the lower edge and is fastened to the back of the large envelope, to provide an outline on the back of such envelope so related to the flap as to represent in combination therewith a first class envelope or compartment as indicated at 13 in Figure 2, it being noted by reference to said figure that the flap 9 and the line 13 will naturally attract the attention of any one immediately the envelope is turned over for the purpose of removing the contents of the large compartment, and thus suggests the necessity of severing the flap 9 to give access to the contents of the small compartment. If the recipient gives his attention to the first class mail matter, he naturally will sever the flap 7, and in those cases where the flap 2 is sealed, the severance of said flap will not only give access to the large compartment, but also to the small compartment at the right hand end thereof.

In Figures 6 and 8, inclusive, a modified type of small envelope is shown. In this type a blank of substantially square form is provided, foldable centrally on line 14 to provide a rear side 15 and a front side 16, the face of the rear side being shown as supplied with adhesive 17 for the purpose of closing the ends of the envelope, though if the side 16 has an end extension 16^a, corresponding to extension 12, the corresponding ends of the sides need not be sealed. The rear side 15 is provided with a top sealing flap 18, and cut out of the lower edge of the said side as at 19 is a corresponding sealing flap 20, adapted to be folded under the lower edge of the large envelope and sealed upon the back thereof in the manner as explained in connection with flap 9.

It will be apparent that a duplex envelope corresponding to Figures 6 and 7 is in all essentials the same as that illustrated in Figures 1 to 4 inclusive, in that in the complete duplex envelope there are two normal top and bottom flaps for the first class compartment severable so that access may be had from either of the two sides of the lower class compartment. It is also similar in that if provided with the extension 16^a fastened to the flap of the large envelope, the severance of the latter will give access to the ends of both compartments.

From the above description it will be apparent that I have produced a duplex envelope embodying the features of advantage set forth as desirable in the statement of the objects of the invention, and which is susceptible of modification in minor particu-

lars without departing from the principle of construction involved.

What I claim is:

1. The combination of an envelope having a closing flap, of a smaller envelope superimposed upon the face of and fastened to the large one and provided with a top and bottom opening and a sealing flap for each of said openings, the top flap folding over the front face of the small envelope to seal the top opening and the bottom flap folding upon the back of the large envelope to seal the bottom opening.
2. The combination of an envelope having a closing flap at one end, of a smaller envelope superimposed upon the face of and fastened to the large one and provided with a top and bottom opening and a sealing flap for each of said openings, the top flap folding over the small envelope to seal the top opening and the bottom flap upon the back of the large envelope to seal the bottom opening, the small envelope also having an end opening and a flap at the same end fastened to the flap of the large envelope and foldable co-incidently with the latter.

In witness whereof I hereunto affix my signature.

ADAM F. TORRANCE.
